BOOSTER CONSTRUCTION FOR EXPLOSIVE BOMBS, &c.

1,317,611.

Specification of Letters Patent. Patented Sept. 30, 1919.

Application filed February 25, 1918. Serial No. 218,928.

To all whom it may concern:

Be it known that I, LESTER P. BARLOW, a citizen of the United States, residing at New Haven, in the county of New Haven 5 and State of Connecticut, have invented certain new and useful Improvements in Booster Construction for Explosive Bombs, &c., of which the following is a specification.

My present invention is an improvement 10 upon the construction described and claimed in my application Serial Number 195,187, filed October 6th, 1917, for booster construction for explosive devices, which construction is adapted for use in various forms of 15 explosive shells in which the booster charge of explosive material is to be fired by the explosion of a detonator and is in turn to detonate the main explosive charge of the shell. In the application referred to an integral frame, preferably a casting, is provided having upper and lower annular portions connected together by radially or outwardly extending ribs. A tube is inserted 20 within the bore of this frame to provide an inner closure for the pockets or spaces between the ribs. The pockets thus formed being filled with detonating material are closed 25 on their peripheries by an outer tube fitted around the frame. In the application referred 30 to this outer tube was simply fitted around the frame to contact against the outer edges of the ribs referred to, the upper edge of the tube preferably abutting against a shoulder formed on the upper annular portion of the frame, the tube being secured in position by peening its lower edge slightly about the lower edge of the bottom 35 annular portion of the frame.

In operation it has been found that this 40 construction does not, in all cases, provide sufficient strength to withstand the shocks to which the construction is subjected when the bomb in which the booster is secured strikes its target. At the moment of impact 45 the shock is communicated from the outer casing of the bomb to the booster frame, and tends to break the radial ribs referred to. The result of such breakage may be to cause inward springing of the frame, and obstruction 50 of the downward movement of the deto-

nator into firing position, or the dropping of the plug carrying the firing pin out of position, in which case the detonator would drop harmlessly into the explosive chamber. My present improvement overcomes this 55 difficulty by utilizing the outer closure for the pockets situated between the radial ribs as a stiffening and strengthening member. Accordingly I secure this outer tube or closure rigidly to the upper portion of the 60 frame, as by screw-threading the same thereon, and bend the lower edge of the tube inwardly to form a sustaining flange located beneath and in close contact with the lower annular portion of the frame. This outer 65 tube may be made of metal and given considerable strength without preventing the shattering of the same and the consequent detonation of the bursting charge of the bomb, when the detonating material in the 70 pockets of the booster is exploded. The booster frame may likewise be stiffened by the provision of a suitable firing plug which may be secured within the lower annular portion of the booster frame. 75

In order that a clearer understanding of my invention may be had, attention is hereby directed to the accompanying drawings forming part of this application and illustrating a preferred embodiment of my invention. In the drawings Figure 1 represents a vertical, longitudinal section through a booster embodying my invention mounted in position within a bomb casing, and Fig. 2 is a horizontal section taken on line 2—2 of 80 85 Fig. 1.

Referring to the drawings a main frame 1, preferably a metallic casting, is employed having upper and lower tubular portions 2 and 3 which are provided at their lower and 90 upper ends respectively with outwardly extending annular portions 4 and 5. These latter are connected by a plurality of outwardly extending vertical ribs 6, which are spaced around the periphery of the structure and preferably extend radially. By this means a skeleton frame is provided which may easily be cast and which affords pockets or spaces between the ribs 6 for the reception of the detonating charge. A thin 95 100

tube 7 of brass, or other suitable material, is fitted within the bore of the frame to have close contact with the inner surfaces of the annular portions 4 and 5 of the frame and 5 to rest against the inner edges of the ribs 6.

- The spaces between the ribs, the horizontal portions 4 and 5 and the tube 7, may then be filled with a high explosive material 8 such as tri-nitro-toluol. The metal tube 9 10 having a screw-thread formed on the upper portion of its bore, as indicated at 10, is then slipped upwardly into position around the frame and screwed into tight engagement with a corresponding screw-thread 15 formed on the periphery of the upper annular portion of the frame, and if desired, on the outer edges of rib 6. The lower edge of tube 9 is curved or bent inwardly, as indicated at 11, to press tightly against the lower 20 surface of the lower annular portion 5 of the booster frame when the tube is screwed into its final position. When so arranged, tube 9 forms a strut member and takes whatever stresses may be transmitted from upper 25 per annular portion 4 to lower annular portion 5. By this means the danger of breakage in ribs 6, or at the angles between annular portions 4 and 5 and the portions 2 and 3 of reduced diameter, respectively, is obviated.

In my preferred construction a plug 12 is screwthreaded within the lower cylindrical portion 3 of the booster frame, this plug preferably being of solid metal and having 35 a peripheral lower flange 13 which may contact against the lower end of cylindrical portion 3 when plug 12 has been screwed into position. This plug serves as a further stiffening means for the construction. A firing pin 14 is secured on or is integral with the upper surface of plug 12.

The upper portion 2 of the booster frame is preferably elongated as shown, and is secured in position within the outer casing 45 15 of the bomb or explosive device, in any suitable manner. In the construction illustrated, the upper end of portion 2 is provided with an outwardly extending annular portion 16 which has an internally threaded 50 ring 17 screwed thereon, this ring being secured to the casing 15, as by means of flange 18 on ring 17 being inserted within a suitable opening in the casing 15. Stiffening ribs 2' may extend between outwardly extending portions 16 and 4 of the frame.

A tube 19 may extend upwardly from the upper portion 2 of the booster frame, preferably being screw-threaded therein, so that its bore forms a continuation of the bore 60 of portion 2 of the detonator frame. A detonator 20 is illustrated as mounted within tube 19, this detonator having an explosive cap 21 at its lower surface, which is connected by a passage 22 with a detonating material 23 carried on the periphery of the

detonator, cap 21 being adapted to be exploded by contact with the firing device 14 or any other suitable firing device. It should be understood that the explosive chamber surrounding tube 9, within the casing 15, is 70 filled with high explosive material which is detonated by the explosion of the explosive material 8 in the booster, when the latter is fired by the explosion of detonating material 23 on the periphery of the detonator. It 75 should also be understood that the shock caused by the impact of the forward end of the bomb against its target, when the bomb is dropped from an aeroplane, for example, causes excessive stresses, which are transmitted from casing 15 to the booster frame. These stresses, acting downwardly through ribs 6 to annular portion 5, would tend to rupture the ribs 6, were it not for the provision of the tubular member 9 which sustains the annular portion 5, the stresses being thereby distributed throughout the periphery of member 9.

What I claim is:

1. A booster construction for explosive 90 shells, comprising a skeleton frame having upper and lower annular portions extending outwardly from a cylindrical bore, peripherally spaced ribs extending between said portions, and a rigid tubular member 95 fitted around the outside of said annular portions and said ribs, said member being secured to said upper annular portion by being screw-threaded thereto, and having its lower edge curved inwardly to form a sustaining flange beneath and in close contact with the lower surface of said lower annular portion.

2. A booster construction for explosive 105 shells, comprising a skeleton frame having upper and lower annular portions extending outwardly from a cylindrical bore, peripherally spaced ribs extending between said portions, and a rigid tubular member fitted 110 around the outside of said annular portions and said ribs, said member being secured to said frame in such manner as to make a rigid connection between said upper and lower annular portions.

3. A booster construction for explosive 115 shells, comprising a skeleton frame having upper and lower annular portions extending outwardly from a cylindrical bore, peripherally spaced ribs extending between said portions, and a rigid tubular member fitted 120 around the outside of said annular portions and said ribs, said member being secured to said upper annular portion by being screw-threaded thereto, and being secured to said lower annular portion to sustain the same. 125

4. A booster construction for explosive shells, comprising a skeleton frame having upper and lower annular portions extending outwardly from a cylindrical bore, peripherally spaced ribs extending between said 130.

portions, a thin tube fitted within the bore of the frame, a firing plug screw-threaded within the lower end of the bore of said lower annular portion below the end of said 5 thin tube, and a rigid tubular member fitted around the outside of said annular portions and said ribs, said member being rigidly secured to said upper annular portion, and

flanged at its lower end into sustaining contact with said lower annular portion. ¹⁰

This specification signed and witnessed this 7th day of February, 1918.

LESTER P. BARLOW.
